UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

PROPELLER.

1,100,942.

Specification of Letters Patent Patented June 23, 1914.

Application filed March 17, 1913. Serial No. 754,757.

To all whom it may concern:

Be it known that I, ADELMER M. BATES, a citizen of the United States, residing at Chicago, in the county of Cook and State 5 of Illinois, have invented a certain new and useful Improvement in Propellers, of which the following is a specification.

My invention relates to improvements in propellers and propelling vanes such as are 10 particularly adapted to propeller feeding of granular material although of course adapted to other uses wherever centrifugal propelling is desirable.

It is illustrated diagrammatically in one 15 form in the accompanying drawings, wherein—

Figure 1 shows an end elevation with the shaft in section; Fig. 2 shows a side elevation with one blade removed; Fig. 3 a plan 20 view of one of the blades.

Like parts are indicated by like letters throughout the several figures.

The shaft A which of course is circular in cross-section, has bolted thereon the two 25 semi-cylindrical sleeve members A¹ held together and to the shaft by the bolt A² and it will be noted that each of these sleeve members carries adjacent either end the flanges or walls A³ A⁴ the outer edges of 30 which are arranged in planes parallel to the tangent to the shaft and at right angles each to the other so as to form a square about the shaft. In the center of each of these flanges is located the bosses A⁵ A⁶ 35 apertured and screw-threaded as at A⁷.

The vanes or blades B rest upon these flanges A³ A⁴ being held in position thereon by the cap-screws B¹ engaging the elongated openings B² therein, these elongated 0 openings being provided for the purpose of permitting greater ease of adjustment. The vanes or blades B are inwardly grooved or depressed as at B³ to give stiffness and also to assist in guiding the vanes in position 5 when they are to be assembled and also to give a certain amount of packing effect in the vanes to facilitate the feeding process. The vanes are outwardly tapered from their

point of connection with the sleeves in a truncated triangular form as indicated so 50 that that part of the vanes where the lineal velocity is greatest will be smallest in cross-sectional area. It will be noted that at one place the flanges A³ A⁴ are approached more closely together than at other points. 55 This is for the purpose of engaging the head of the bolt A² to hold it against rotation thus facilitating an assembly.

The operation of the device is of course self-evident. When the shaft is rotated the 60 propeller will tend to discharge centrifugally any material coming in contact with it and preferably will be in any suitable form of jacket or propelling machine or housing which it is not here necessary to 65 show. All that will be necessary will be to provide means for the material to approach the mill together with a passage by which the propeller may discharge it away from itself.

It will be evident that while my device 70 is operative, still many changes might be made in size, shape and arrangement of parts and I wish therefore that my drawings be regarded as in a sense diagrammatic 75 in order that I be not limited in the scope of my invention to the precise arrangement of parts therein shown.

I claim:

A propeller comprising a shaft engaging a 80 sleeve, bosses projecting outwardly therefrom, flanges projecting outwardly from said bosses, propeller vanes mounted upon said flanges, said propeller vanes being perforate and a cap screw screw-threaded in 85 said bosses and passing through the perforations in said vanes to hold the vanes in position.

In testimony whereof, I affix my signature in the presence of two witnesses this 14th 90 day of March 1913.

ADELMER M. BATES.
